(57) **CLAIM**

The ornamental design for a wall mount bracket, as shown and described.

DESCRIPTION

FIG. 1 is a top, front, left perspective view of a wall mount bracket showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uneven-length broken lines immediately adjacent to the shaded area define the bounds of the claimed design and form no part thereof. The even-length broken lines depicting the remainder of the wall mount bracket show features that form no part of the claimed design. The zig-zag broken lines and brackets shown in the wall mount bracket in FIGS. 1-3 and FIGS. 6-7 indicate a symbolic break in its length. The appearance of any portion of the article between the break lines forms no part of the claimed design.
